GEORGE K. DAVOL, OF SAN FRANCISCO, CALIFORNIA.

PISTON FOR INTERNAL-COMBUSTION ENGINES.

1,156,590.

Specification of Letters Patent.

Patented Oct. 12, 1915.

Application filed October 5, 1911. Serial No. 652,921.

To all whom it may concern:

Be it known that I, GEORGE K. DAVOL, a citizen of the United States, residing at San Francisco, in the county of San Francisco and State of California, have invented certain new and useful Improvements in Pistons for Internal-Combustion Engines, of which the following is a full, clear, concise, and exact description, reference being had 10 to the accompanying drawings, forming a part of this specification.

My invention has particular application to those internal combustion engines in which it is desirable for any purpose to present to the working gases within the cylinder, surfaces heated to a considerable temperature. This is sometimes desirable in order to insure the complete combustion of heavy oils, or tarry constituents of gas, or 20 other fuels, with the proper combustion of which cold surfaces would interfere.

The end of the piston in all internal combustion engines is presented to the working gases or burning charge, and it is usually 25 kept cool either by direct water cooling or by the conduction of its heat to the sides of the piston. In cases where it has been desirable, however, it has frequently been proposed to attach to the end of the piston, a 30 shield, plate or cap, between which and the piston proper would be interposed a layer or thickness of some insulating substance, or some substance which was a poor conductor of heat, and such arrangements have been 35 tried. It has been found, however, in trying such devices, that it is exceedingly difficult to secure such a cap or shield to the end of the piston, so that it would at all times tightly clamp and hold the thickness of 40 non-conducting material in place owing to the effect of the heat in expanding the bolts or other means of attachment which secures the shield to the piston. It has been found that if the slightest looseness be allowed to 45 the non-conducting or insulating layers, that is, if it is not at all times tightly compressed against the end of the piston, it will very quickly abrade, disintegrate and wear away through the reciprocating movement 50 of the piston together with the effect of the high temperatures and the movements of the gases. To overcome this difficulty and to provide an efficient means of securing such a cap or shield to the end of the piston, I 55 employ a metal spring, arranged to exert a constant pull holding the cap or shield

against the end of the piston, the spring being so designed that it will give to, or take up any expansion of the various parts or connections affected by the heat without having the force of its pull appreciably affected. Between the cap or shield and the piston proper, I interpose a layer of asbestos, magnesia, or other suitable poor conductor of heat, which will stand the high temperatures, and this layer of material is always kept by the action of the spring tightly pressed against the end of the piston.

In the accompanying drawings,—Figure 1 shows a section taken through the center axis of a piston connected to a piston rod. Fig. 2 shows a section taken through the center axis of a trunk piston designed to hold a wrist pin for direct connection to a pitman or connecting rod. Fig. 3 shows a section taken through the center axis of a trunk piston designed to be directly connected to a cross-head.

In all the figures the same numerals refer to the same parts.

Referring to Fig. 1, the piston proper 1, which is connected to the piston rod 2, has a shield or cap 3 which is made to fit on a shoulder 4 formed on the end of the piston. Between this cap 3 and the piston is interposed a layer or layers of sheet asbestos or other suitable insulating material 5. The cap 3 is drawn against the end of the piston by two or more rods 6 which are screwed into the cap and pass through the end of the piston. Each of these rods 6 passes through a helical spring 7 and has secured to its end a washer 8 against which the spring 7 bears. Each of the springs bears at its other end against a circular plate 9 through which the piston rod passes and which rests on a shoulder formed on the piston rod. It will now be understood that the springs, bearing at one end against the plate 9 exert a pressure against the washers 8 on the ends of the rods 6, and so through the rods 6 pull the cap or shield 3 against the end of the piston, clamping the layer of non-conducting material tightly in place. By this arrangement the effects of the heat in elongating the rods 6 or other parts will not cause a loosening of the insulating material 5.

In Fig. 2, I show a trunk piston with a modified arrangement of parts. In this case the insulating material 5^a is placed inside of the shoulder 4^a and is thus more protected from the direct action of the gases. In this

form I use one central rod 6^a to draw the cap 3^a against the piston 1^a, and one spring 7^a. All these parts are placed behind the wrist pin 10 and connecting rod 11. As the 5 action of the various parts is the same as explained in describing Fig. 1, this view requires no further explanation.

In Fig. 3 I show a trunk piston designed to be connected directly to a cross-head 12 10 in connection with a modified embodiment of my invention. In this case I draw the shield 3^b against the end of the piston 1^b by a long central rod 6^b which passes through the entire length of the piston and 15 is acted upon by a spring 7^b placed at the outer end of the piston. This arrangement keeps the spring well away from the heat. In this case the non-conducting material 5^b is held inside of a recess turned on the end 20 of the piston.

In these embodiments of my invention I use helical springs for drawing the cap or shield against the piston and I prefer such springs for the purpose. But it must be understood that other forms of springs may be used, such as flat metal springs, or the proper arrangement of elastic material such as india rubber, which would form an equivalent construction. It may be said that all 25 materials are elastic and that a long rod in tension would form a spring, but such a construction would probably not afford sufficient elasticity. My invention is intended to cover any equivalent construction where- 30 by the elasticity of any material is intentionally utilized to afford an elastic pull holding a cap or shield against the end of a piston.

Although the construction covered by this 40 invention is of particular value when a soft insulating material is interposed between piston and cap or shield, such insulating material may be omitted permitting direct contact between piston and cap, and the heat 45 flow retarded by reducing as much as possible the extent of such direct contact.

What I claim is:

1. In an internal combustion engine, the combination of a cylinder, a piston capable 50 of reciprocation in said cylinder, a protective cap substantially covering the end of of the piston which would otherwise be exposed to the working gases, said cap being held against the end of the piston by spring 55 pressure.

2. The combination of a piston for internal combustion engines, a cap or shield, for the working end of the piston, a layer or thickness of non-conducting material inter-

posed between the said cap or shield and the 60 said piston, and a spring or springs arranged to draw the said cap or shield and the said piston together.

3. In an internal combustion engine, the combination of a cylinder, a piston capable 65 of reciprocation in said cylinder, a protective cap or shield substantially covering the end of the piston against which the working gases act, and a helical metal spring or springs holding said cap against the end 70 of the piston.

4. In an internal combustion engine, the combination of a cylinder, a piston capable of reciprocation in said cylinder, a protective cap or shield substantially covering the 75 inner end of the piston against which the working gases act, and one or more helical metal springs disposed within said piston and arranged to draw said cap or shield against the said inner end of the piston. 80

5. In an internal combustion engine, the combination of a cylinder, a piston capable of reciprocation within said cylinder, the inner end of said piston being constructed to receive the pressure of the working gases 85 within the cylinder, a protective cap or shield substantially covering said inner end of the piston, a rod or rods secured at one end to said cap or shield and extending into said piston, and a spring or springs engaging the inner end of said rods to hold the cap against the piston. 90

6. The combination of a piston for internal combustion engines, a cap or shield for the working end of the piston, a layer or 95 layers of nonconducting material interposed between the said piston and the said cap or shield, a rod or rods engaging with the said cap or shield and passing through the end of the said piston, and a spring or 100 springs engaging with the said rod or rods.

7. The combination of a piston for internal combustion engines, a cap or shield for the working end of the piston, a central rod engaging with the said cap or shield 105 and passing through the end of the said piston, and a spring or springs engaging with the said central rod and arranged to draw the said piston and the said shield together. 110

In witness whereof, I hereunto subscribe my name this 29th day of September A. D., 1911.

GEORGE K. DAVOL.
